V. ADAMS,
VAPOR HEATER FOR ENGINES,
APPLICATION FILED APR. 6, 1920.

1,356,482.

Patented Oct. 19, 1920.

WITNESS:

UNITED STATES PATENT OFFICE.

VICTOR ADAMS, OF LEXINGTON, KENTUCKY.

VAPOR-HEATER FOR ENGINES.

1,356,482.

Specification of Letters Patent. Patented Oct. 19, 1920.

Application filed April 6, 1920. Serial No. 371,643.

To all whom it may concern:

Be it known that I, VICTOR ADAMS, a citizen of the United States, residing at Lexington, in the county of Fayette and State 5 of Kentucky, have invented new and useful Improvements in Vapor-Heaters for Engines, of which the following is a specification.

This invention relates to internal combustion engines and has for its object the provision of a cylinder block or cylinder head construction providing passages for the fuel extending adjacent and across the combustion chambers whereby the vaporized fuel 10 will be thoroughly preheated before its introduction into the cylinders through the intake valves, the advantage being that this heating of the vapor increases its combustibility and thereby economizes in fuel consumption while improving the running of 15 the engine and increasing the power derived therefrom.

An important object is the provision of a device of this character which will be simple and inexpensive in manufacture as the heating passages are formed within the cylinder block or head when the same is cast.

An additional object is the provision of a device of this character which will be highly efficient in operation, durable in service, and a general improvement in the art.

With the above and other objects and advantages in view, the invention consists in the details of construction to be hereinafter 30 more fully described and claimed, and illustrated in the accompanying drawings in which,

Figure 1 is a longitudinal vertical sectional view through an engine having my 40 heating means associated therewith the section being taken on the line 1-1 of Fig. 2;

Fig. 2 is a horizontal sectional view on the line 2-2 of Fig. 1, and

Fig. 3 is a vertical cross sectional view on the line 3-3 of Fig. 2.

Referring more particularly to the drawings, the numeral 10 designates the cylinder casting which has the usual cylinders 11 and which includes the usual water jacket 12. 50 The type of cylinder casting does not affect the present invention though the block is shown in the present instance as being of the L-head type and provided with intake valve openings 13. The numeral 14 designates 55 the pistons connected with the usual connect-

ing rods 15, and 16 designates the intake valves. The exhaust valves are not shown as not having any bearing upon the present invention.

In carrying out my invention I provide 60 an intake manifold 17 which is cast with the cylinder block and which has its end 18 leading to one side of the casting. The manifold includes branches 19 which extend in opposite directions and which extend to 65 all of the cylinders. Formed integrally with the casting and extending transversely of the cylinders are conduits 20 which lead from the branches 19 of the manifold at substantially right angles thereto and which 70 are disposed in spaced relation to the tops of the cylinders and the intake valves 16. The intake valve openings 13 are disposed at the juncture of these conduits with the lower wall forming the combustion chamber 75 and the conduits 20 are then expanded in size to define chambers 21 beneath the intake valves, it being apparent that the conduits are curved downwardly.

In the operation it will be seen that the 80 combustible vapor entering the intake manifold must, before it reaches the intake valves, pass through the conduits 20 and as these conduits extend across the combustion chambers it is readily apparent that the 85 vapor will be thoroughly heated before it is admitted by the valve 16 into the combustion chamber. This preheating insures that the vapor will be in proper condition for ignition so that complete combustion will take 90 place and the running of the engine improved.

From the foregoing description and a study of the drawings it will be apparent that I have thus provided an engine construction in which the heating means is contained entirely within the cylinder casting 95 so that likelihood of breakage or derangement will be reduced to the minimum and wherein the heating effect is accomplished 100 entirely by the heat generated within the engine without any necessity whatever for the employment of extraneous means.

While I have shown and described the preferred embodiment of my invention, it is 105 of course to be understood that I reserve the right to make such changes in the form, construction, and arrangement of parts as will not depart from the spirit of the invention or the scope of the subjoined claim. 110

Having thus described my invention, I claim:

In an internal combustion engine, a cylinder casting having cylinders formed therein, an intake manifold formed integrally within said casting and having one end extending beyond one side thereof for connection with a carburetor or a vaporized fuel conduit, said manifold being branched 5 whereby to extend to all the cylinders, conduits formed integrally with said manifold

and extending at substantially right angles thereto transversely of the cylinders, the casting being further formed with chambers adjacent the cylinders with the chambers 15 provided with valve controlled openings communicating with the cylinders, and the conduits being downwardly curved and merging into said chambers.

In testimony whereof I affix my signature. 20

VICTOR ADAMS.
